COIN CHUTE

John Bauer, Sunnyside, and Max Grau,
New York, N. Y.

Application February 20, 1940, Serial No. 319,816

2 Claims.

(Cl. 133—6)

This invention relates generally to coin chutes, but more specifically to coin chutes adapted to be affixed to ladies' handbags for purposes of withdrawing coins for immediate use without the necessity of opening the handbag.

The main object of the invention resides in the provision of a coin chute adapted to be affixed to ladies' handbags wherein the end or outlet of the chute is externally disposed of the pocketbook, the said end having pivoted ejection means for the withdrawal of a single coin at a time.

A further object of the invention resides in the provision of a coin chute of the above nature which is capable of storing a plurality of coins after feeding; wherein means are provided for the prevention of loss of coins in the chute in the event that the handbag or pocketbook is in inverted position; wherein the ejector means when in position of withdrawal of a coin stops passage of the next consecutive coin; and wherein the ejector means is normally in closed and locked position at all times except when outward finger pressure is applied for coin withdrawal.

A further object of the invention resides in the provision of a coin chute which is economical to manufacture, easy to assemble and mount on a handbag, which contains a minimum number of parts, which is efficient in operation and simple to operate.

These objects and other incidental ends and advantages of the invention will hereinafter appear in the progress of the disclosure and as pointed out in the appended claims.

Accompanying this specification are drawings showing preferred forms of the invention wherein corresponding reference characters designate corresponding parts throughout the several views and wherein:

Figure 1 is a front view in elevation of a typical handbag showing a coin chute attached therein.

Figure 2 is an end view in elevation partly in section showing the coin chute secured within the bag.

Figure 3 is a front view in elevation of the coin chute.

Figure 4 is a top plan view of one side of the coin chute and an ejector member secured thereto.

Figure 5 is a plan view of the coin chute with the ejector member in closed position.

Figure 6 is a fragmentary view in elevation of Figure 4 showing the ejector member in open position releasing a coin.

Figure 7 is a front view in elevation of a handbag formed with metallic frame showing a coin chute attached thereto.

Figure 8 is an end view in elevation of Figure 7.

Figure 9 is a top plan view of the handbag shown in Figure 7 in closed position.

Figure 10 is a view similar to Figure 9 showing the handbag in partially open position and exposing the mouth or inlet of the coin chute.

In accordance with the invention and in accordance with the preferred forms shown, a handbag provided with the usual front and rear walls 10 and 11, bottom wall 12 and side walls 13 is illustrated. The walls 10 and 11 are each provided with the usual lining 14, the said front and rear walls together with the lining being secured to the bottom wall 12 in any known manner such as by lines of stitching 15, the front and rear walls also being secured to the side walls 13 by the usual lines of stitching at the positions indicated by numeral 15'.

In addition to lining 14, the handbag shown is provided with an inner lining indicated by numeral 16, the said lining being secured at the upper portion 17 to the lining 14, there being an opening in the inner lining as indicated by numeral 18, whereby the inlet or mouth of the coin chute mounted between the inner lining 16 and the lining 14 is exposed to the interior of the handbag. Numerals 19 and 20 indicate any conventional means of locking the handbag, the said means 19 and 20 being in the form of engaging lugs secured to the upper inner portions of the pocketbook walls.

The coin chute generally designated by numeral 21 is preferably comprised of two similarly shaped and preferably metallic plate members indicated in Figure 3 by numerals 26 and 42. Plate member 26 has an inlet portion 22 with a concave cutout 23 and outwardly flared wing portions 24 and 25 adjacent thereto. The inlet portion 22 communicates with an inclined intermediate portion 26', the latter terminating in a flared outlet portion 27. Plate member 26 along its longitudinal edges is provided with walls 28 and 29.

At the inlet portion 22 are lugs 30 and 31 which are adapted to secure plate 26 of the coin chute to the handbag by penetrating the lining thereof as shown in Figure 2 and then being folded over thereagainst, while at the outlet portion 27 is a bracket member 32 adapted to engage an edge of the handbag side wall 13 through an opening 15'' in the stitching connecting the front and side walls along the area 15'. The outlet portion 27 of plate member 26 and the outlet portion of plate member 42 when said plates are assembled, as will hereinafter appear, penetrate opening 15'' at extension portions 33 and 43. It is thus seen how the coin chute by means of securing members 30, 31 and 32 is anchored within the handbag between lining 14 and inner lining 16.

Along walls 28 and 29 of plate 26 are a series of lugs 30' and 31' adapted to engage and be folded over the aforementioned plate member 42,

plate members 26 and 42 spaced by walls 28 and 29 forming the chute.

A leaf spring 34 secured along wall 28 adjacent portion 27 of plate 26 is adapted to normally engage a lower curved edge 35' of an ejector member 35, the said ejector member being pivotally secured between extensions 33 and 43 by a rivet 36. The inner wall 37 of ejector member 35 is curved to conform to the circular shape of a coin 41 while the upper end of member 35 is provided with a depression 38 to engage a projection 39 on portion 27 to serve as conventional locking means for ejector member 35 when in normally closed position. To facilitate the withdrawal of ejector member 35 from within the outlet portion of the coin chute, the projecting portion of said ejector member as shown in Figure 1 is provided with curved depressions 40 on its faces whereby the operating fingers of the user may grip the ejector member for purposes of opening the same about rivet 36 and against the action of leaf spring 34. Leaf spring 34 maintains the ejector member 35 closed at all times except when pulled outwardly by the finger, at which time the coin carried thereby in inner curved edge 37 is grasped for withdrawing purposes. Upon the removal of the coin, the ejector member 35 is automatically closed by the action of leaf spring 34. It is to be noted that the lower edge 35' of the ejector member 35 when the latter is pulled outwardly abuts against the end of wall 28, thereby serving as a limiting position of the ejector member as shown in Figure 6. The upper portion of edge 35' serves as a stop for the passage of the coin 41 adjacent to the coin resting within curved edge 37 of the ejector member. Each time a coin is withdrawn from the coin chute, the ejector member automatically closes and the opening operation repeated for the withdrawal of needed additional coins.

The aforementioned plate member 42 of the coin chute is of the same general shape as plate member 26, the inlet end having flared wing members 44 and 45. Between wing members 44 and 45 is an intermediate extension 46 having a projection 47 on the inner wall whereby coins are forced into the chute for feeding purposes. Coins are thus prevented from escape from the coin chute in the event that the latter assumes an inverted position when the handbag is accidentally turned into such position. The integration of the plate members 26 and 42 forming the coin chute is accomplished by bending lugs 30' and 31' over the outer face of plate 42 as best shown in Figure 53, and as heretofore mentioned.

Figures 7, 8, 9 and 10 show a coin chute affixed to a handbag having a framework. The bag is the ordinary type of bag having front and rear walls 48 and 49, a bottom piece 50, and side pieces 51. The bag is provided with a metallic frame secured to the mouth portion of the bag, the said frame consisting of a set of similar channel frame-pieces, one frame piece having leg members 52 and a top member 55, the other frame piece having leg members 53 and a top member 56, the lower ends of the leg members being joined by hinges 54. The channel frame-pieces are adapted to penetrate the upper side portions and the top edges of the bag and be secured thereto in any well known manner. The top member 56 is provided with a spring latch 59 pro-

jecting beyond the inner edge thereof as shown in Figure 9 and is adapted to engage a lug 58 on top member 55, the latch extending across the width of said top member 55. The inlet of the chute is slightly modified from that shown in Figures 1 to 6 inclusive, whereby the inlet is affixed to the under side of top member 55 and communicates with a slit 57 therein and whereby the outlet is affixed to the inner side of leg 52 and communicates with openings 60 and 61 therein. The inlet of the chute below slit 57 is provided with a projection 47' to prevent coins from being lost therethrough when the pocketbook is inverted, and has the same purpose as projection 47 in the type of chute shown in Figures 1 to 6. It is to be noted that slit 57 is covered by latch 59 when the bag is in closed position.

We wish it understood that minor changes and variations in the material, integration, location, combination and subcombination of parts may all be resorted to without departing from the spirit of the invention and the scope of the appended claims.

We claim:

1. A coin chute adapted to support coins edge to edge therewithin, including a vertically disposed flat tubular body having an inlet at one end and an enlarged flat tubular discharge chamber in the plane of the coins communicating with said tubular body at the other end and having an outlet, the lower portion of said outlet having projecting side walls, a carrier pivoted in the discharge chamber between said projecting side walls adapted to swing in and out of said outlet and having a semicircular inner edge conforming to the lower half of a coin to engage and serve as a stop for the bottom-most coin in the tubular body when said carrier is in normally closed position, the said carrier when moved to extended position conveying the lowermost coin partly beyond said outlet to a conveniently withdrawable position, the inner end of the carrier adjacent the semi-circular inner edge preventing the passage of the next consecutive coin from within the tubular body and the projecting side walls serving as guides for the support of the extended coin.

2. A coin chute adapted to support coins edge to edge therewithin including an elongated flat tubular body having an inlet at one end and being expanded in the plane of the coins into an enlarged discharge chamber at the other end and having an outlet, the lower portion of said outlet having projecting side walls, a carrier pivoted in the discharge chamber between said projecting side walls adapted to swing in and out of said outlet, and a spring for holding said carrier in normally closed position and said carrier having a semi-circular inner edge conforming to the lower half of a coin to engage and serve as a stop for the bottom-most coin in the tubular body when said carrier is in normally closed position, the said carrier when moved to extended position conveying the lowermost coin partly beyond said outlet to a conveniently withdrawable position, the inner end of the carrier adjacent the semi-circular inner edge preventing the passage of the next consecutive coin from within the tubular body and the projecting side walls serving as guides for the support of the extended coin.

JOHN BAUER. 70
MAX GRAU.
